DISPLAY BOX

Bruce J. Davidson, Kew Gardens, N. Y., assignor
to National Biscuit Company, New York, N. Y.,
a corporation of New Jersey

Application September 25, 1931, Serial No. 565,046

7 Claims. (Cl. 206—44)

My invention pertains to boxes and particularly to that type of box that serves as a container for shipping merchandise and also is used to attractively display the goods to prospective customers.

Such boxes are usually made from card board or other light and cheap material that may be printed or decorated in attractive colors and designs, and in which the cover or other part of the box may be bent or turned under the body so as to support it with its open top in an inclined position to display the contents. It is apparent that such boxes will display their contents more advantageously and effectively, the higher the angle to which the box can be tipped or raised. As heretofore constructed, the boxes could be tilted or have their back end raised only through a very small angle, because the extent to which the box could be tilted was limited by the height of the cover or other means used to support the box. With such boxes supported at a low angle, the goods are well displayed when the box is full, but when part of the goods has been sold, that remaining can not be seen effectively unless the box is very shallow.

As a result, display boxes have been made relatively shallow, which results in their being wide, for a stated cubical content, and therefore occupying a large area of counter space in the store. For this reason, many merchants refuse to place these displays on their counters because they take up too much valuable space.

The present invention is designed to overcome these disadvantages and has among its several objects to produce a display box that can be supported at a high angle when in display position, that is relatively deep, and will occupy very little space on the counter. My improved box also has these advantages that it is stable in display position, effectually displays the contents at all times, regardless of the degree of fullness of the box, and requires less material to make a box having a given cubical content than is required for a wide shallow box of the same volume. The box also is easy and cheap to manufacture because it can be formed from a single piece or blank. Another important advantage of my invention is that the box is held in display position by placing the support, (which is shown as a part of the cover) under one end of the box to keep it from tipping forward, as distinguished from the bottom of the box as is usual in display boxes of this character, and another part of the cover or other means bears against the bottom

of the box, which is nearly vertical, and braces the box against overturning.

The above and other objects and advantages are obtained by the two embodiments of my invention illustrated in the accompanying drawings wherein

Fig. 1 is an isometric view of a box embodying a preferred form of my invention, the box being shown in display position.

Fig. 2 is a vertical section through the box of Fig. 1.

Fig. 3 shows the box in closed position, part being broken away to show the hinged connection of the cover to the box.

Fig. 4 shows the single piece blank from which the box and cover are made.

Fig. 5 shows a slightly modified form of box embodying the invention.

Fig. 6 is a vertical section through the box of Fig. 5.

Fig. 7 shows the box in closed position.

Fig. 8 is the blank from which the box and cover are formed; and

Fig. 9 shows a price card that is adapted to be interlocked with the box when the blank is folded into box form, and lies under the cover when the box is closed, but can be raised to stand above the box, as shown in Fig. 5, when the box is in display position on the counter.

The blank from which my improved display box is formed is shown in Fig. 4 wherein the body of the box is formed from the bottom panel 10, the two end sections 11, 12, the two side sections 13, 14, and the tongues 15, 16, 17, and 18, which interlock to hold the side and end sections in position as is usual in the art. A price tag or display panel 19 may be formed integral with the end section 11, being separated therefrom by a score line 20. The top edge of the end section 12 joins a hinge section 21 which connects the cover to the body portion of the box.

The cover has a top panel which is divided by a score line 22 into two sections 23, 24, the section 23 being connected to a section 25, which forms one end flange of the cover. At the opposite end, the cover has an end flange 26 which is shown as of the same depth as the flange 25 and also of the same depth as the hinge section 21 which connects the cover to the body of the box, but may be of any depth desired.

The cover also has side flanges which have been cut away by triangular notches so as to form two triangular flanges 27, 28 and two side flanges 29, 30, which are preferably made in the shape of a trapezium. The apices of the

triangular flanges 27, 28 and the points of the notches in the cut-away sides coincide with the score line 22 and at their bases are provided with the tongues 31, 32, which interlock to hold the side flanges 27, 28 and the end flange 25 in position. The trapezial sections 29, 30 have locking tongues 33, 34 and wing sections 35, 36, the wing sections being adapted to be folded along the score lines 37, 38 so that they lie against the sections 29, 30, while the tongues 33, 34 interlock with slits in the end flange 26 to hold the two sides and end of the cover in position. The wings 35, 36 are folded in against the sections 29, 30 so as to give a rigid bearing to this section of the cover when the box is in display position.

When forming the box from the blank illustrated in Fig. 4, the sides and end of the body of the box are bent along the score lines, which are indicated by dotted lines in this figure, until they are at right angles to the bottom of the box when the tongues 15, 16, 17, and 18 are interlocked to secure the body of the box in box forming relation. The wings 35, 36 are then folded inwardly against the sections 29, 30, and the end flange 26 turned up at right angles to the panel 24. The tips of the wings 35, 36, extending beyond the score lines shown thereon, will overlap the tongues 33, 34 which are then bent inwardly and interlocked in the slots shown in the end flange 26.

The blank is next bent on the score line 39 so that the panel 25 will form an end flange of the cover, and the tongues 31, 32 are interlocked to hold the flanges 25, 27, 28 in position. The box and cover are now completely formed, the cover being connected by the hinge section 21, which joins the lower edge of the flange 25 to the top edge of the end 12. The hinge 21 is scored along both edges, as indicated, so that it forms a hinged connection between the cover and the body of the box. The cover can now be swung about this hinged connection to close the box, the hinge 21 lying inside of the end flange 25 and outside of the end 12 of the box, as indicated in Figs. 2-3.

When the box is filled with merchandise and shipped, it is closed as shown in Fig. 3 with the price or display card 19 folded down flat under the cover.

When the merchant receives the package, he swings back the cover on the hinged portion 21 and turns that part of the cover, formed by the panel 23 and triangular flanges 27, 28, down against the end 12 of the box. The other part of the cover, formed by the section 24 and trapezial flanges 29, 30 and end flange 26, is bent back on the score line 22 so that the panel 24 lies against the bottom of the box. When this has been done the sections of the cover occupy the position shown in Figs. 1-2 and the hypotenuse of the triangular sections and the base of the trapezial sections lie in a straight line and form a support for the box, which can then be placed on the counter with one end resting on the triangular section and the back braced by the trapezial sections. It will be noted that the portions cut from the cover flanges to provide the flanges 27, 29 and 28, 30 are right angled triangular sections so that the panels 23, 24, when bent on the score line 22, form a dihedral angle of substantially 90° and the edges of the triangular and trapezial sections lie in a straight line when the box is in display position. The doubled-down portions 35, 36 serve to strengthen the trapezial sections 29, 30 and give them additional rigidity

to support or brace the bottom of the box, which becomes the back side of the box when it is in display position.

The price card 19 can now be raised into the position shown in Figs. 1-2 and preferably bears a price legend or other matter advertising the goods which are displayed in the box.

It will be noted that my improved box is tilted at a very high angle when in display position and that any merchandise contained therein can be readily seen by the prospective purchaser even through the box be nearly empty. Also, the box being supported on its end and being relatively deep, will occupy very little space on the counter.

The modified form of my invention, shown in Figs. 5-9, is similar to that just described in all its principal features, except that the price card is preferably formed from a separate piece and the cover is hinged to the box at its opposite end. The body of the box has a bottom panel 40, sides 41, 42, and end 43, and tongues 44, 45, 46, and 47 which interlock at the two ends of the box to hold the sides and ends in position. A price panel 48 is divided by a score line 49 into two parts, the shorter part having a slit 50 which interlocks with one of the flaps on the tongues 46, 47 to secure the panel in the box, the panel being bent on the line 49 so that it will lie under the cover when the box is closed.

The cover has two top panels or sections 51, 52 which are separated by a score line 53, and at one end it has two triangular side flanges 54, 55, having flaps 56, 57 which interlock with the end flange 58 to form one part of the cover. The flange 58 is separated by a score line 59 from a section 60, which has a lip 61 adapted to be folded around the flaps 56, 57 and the lip 61 tucked under the tongue 62 to hold the end of the cover in position.

The panel 51 has two trapezial side flanges 63, 64 which are provided with flaps 65, 66, similar to the flaps 35, 36 of Fig. 4. The panel 51 is joined to a section 67 which forms both an end of the box when the cover is closed and a hinge section connecting the cover to the box, about which the cover may be moved from closed to display position. The end section 67 is joined to two short sections 68, 69, separated by score lines and provided for the purpose of permitting the section 67 to serve its double function. The sections 68, 69, form a filler section that serves to connect the hinge or end panel 67 to the bottom panel 40 and their length will vary with the depth of the box. The height of this section is equal to the difference in length between the end 67 and the combined length of the tongues 46 and 73, or 47 and 72. In case the length of the panel 67 and depth of the box equals the combined length of tongues 46 and 73, then the section 68, 69 will disappear, and the panel 67 will join directly to the bottom 40.

In forming the box from the blank shown in Fig. 8, the sides 41, 42 and end 43 are bent up into vertical position. At the opposite end, the panel 69 is then bent upward into a vertical plane 65 and the panel 68 bent back so that it lies outside of the section 69. The short end of the price panel 48 is then placed with its lower edge between the section 68 and the two tongues 46, 47, which are bent inwardly and interlocked outside of the price card and the sections 68, 69, with the flap on the tongue 46 interlocking with the slit 50 in the price panel. The sections 68, 69 thus form a short double section projecting up inside of the box, the end panel 67 at this time lying wholly

outside of the box, with the score line 78 coinciding with the lower edge of the box.

The parts of the cover are now folded into position and interlocked to form a cover with an end flange 58, two triangular side flanges 54, 55, and two trapezoidal side flanges 63, 64, one end of the cover being joined to the panel 67 at the score line 71.

The panel 67 is now bent upwardly until it contacts with the end of the box and forms an outer end panel for the body of the box, the two tongues 72, 73 having been interlocked to form an end flange for the cover. At the same time that the panel 67 is swung upwardly, the blank is bent along the score line 71 so that the cover flange formed by the sections 72, 73 comes in contact with the end of the box and the cover is swung down into closed position, as shown in Fig. 7, with the price panel 48 lying inside of the cover.

When the merchant receives the box, it is filled with merchandise and closed, as shown in Fig. 7, but on opening the box, the cover is turned back so that the end panel 67 engages with the bottom of the box, as shown in Fig. 6, and the panel 51 of the cover also engages the bottom of the box with the panel 52, the triangular flanges 54, 55 engaging the end 43 of the body of the box, as shown in Figs. 5-6.

With the cover of the box in this position, the merchant places the box on the counter, resting on the triangular sections 54, 55, and that part of the cover having the trapezoidal sections 63, 64 forms a brace for the back or bottom of the box to prevent its overturning. The price tag can now be bent into vertical position and the contents of the box will be advantageously displayed to the prospective customer. It will be noted that the box, when in display position, is supported at such a high angle that even when the box is nearly empty the few remaining articles will still be visible to anyone passing in front of the box.

It will be noted that the angle between the two sections of the cover flange is a right angle, that is, the base of the trapezoidal section is at right angles to the hypotenuse of the triangular section. When the cover is folded back to support the box in display position, these two sides lie in a straight line or in the same plane. Consequently, the two sections 23, 24 (or 51, 52 as the case may be) now lie at right angles to each other and form a cradle or support for the bottom and one end of the box.

In the above noted description of the method of folding the blank to form the box, it will be understood that the exact sequence described need not be followed but that the description given is illustrative of only one method of folding the blank, and the sequence of operations may be varied to suit the convenience of the person or machine that folds the blanks.

While I have disclosed two specific embodiments of my invention, it will be understood that these are but illustrative, and are not to be considered as limitations of the invention. It will be apparent to those skilled in the art that these can be incorporated in many different modifications, and I claim as my invention all such modifications and forms as come within the scope of my claims.

What I claim is:

1. In a display box, a box body, a cover said cover having a top panel and end and side flanges, the side flanges having triangular notches intermediate their ends extending to the top panel and providing a triangular flange on

each side of the top panel, the top panel having a transverse score line extending between the points of the triangular notches and dividing the top panel into two portions, the length of one of said portions and the adjoining triangular flanges being substantially equal to the depth of the box, a connection formed from the material of the box connecting the cover and box body, said connection being constructed and arranged so that said triangular flanges and adjacent cover portion can be turned into contact with one end of the box and provide an inclined support therefor and the other portion of the cover forming a brace for the bottom of the box.

2. In a display box, a box body, a cover, said cover having a top panel and end and side flanges, the side flanges being cut away so as to form two opposite triangular sections and two opposite trapezium-shaped sections, the length of the triangular sections being substantially equal to the height of the box, the top panel being foldable transversely at the points of the triangular sections, and when so folded that part of the cover having the triangular sections forming an inclined support for one end of the box, and that part having the trapezium sections forming a brace for the back or bottom of the box, the angle between the adjacent edges of the triangular and trapezoidal sections being such that when the cover is folded and the box placed on the support the trapezoidal sections will contact with the back of the box throughout their length and the triangular sections will contact with the end of the box throughout their length.

3. In a display box, a box body, a cover for the box having an end flange, triangular side flanges on the cover, the base of the triangular flanges being equal to the height of the end flange and adjoining the same, the altitude of the triangular flanges being substantially equal to the height of the box body, and a hinge section connecting the cover to the box, said hinge section being of substantially the same height as the cover end flange; whereby the said end flange and triangular flanges may be turned under and support the end of the box, and means on the cover adjoining the apices of the triangular flanges forming a brace for the rear of the box to prevent its overturning.

4. In a display box, a box body having a bottom and four sides, a cover having a flat top and side and end flanges, each side flange being cut away intermediate its ends to provide a triangular section at one end and a trapezoidal section at the opposite end, the two sections being adjacent at the apex of the triangle and base of the trapezium, the angle between the adjacent sections being a right angle, the cover having a score line joining the apices of the triangles, said cover being foldable on said score line until the adjoining sides of the triangular and trapezoidal sections lie in a straight line thereby providing a right angled cradle for supporting the end and bottom of the box.

5. In a display device, a box, a flanged cover therefor, the side flanges of the cover having opposite right angled portions cut therefrom, thereby dividing each flange into two sections, one of which is a right angled triangle, the two triangular sections being similar and opposite on the cover, the cover having a score line joining the apices of the triangular sections and folded thereon to form a dihedral angle of substantially 90° and the edges defined by the cut out portions lying in a straight line, said box being supported

in said dihedral angle with one end resting on said triangular sections and the bottom braced by the other two sections throughout their height.

6. A carton blank formed from a single piece 5 of material having defined thereon by score lines a cover end flange, a top panel, a second cover end flange, a hinge section, a box end, a bottom section and a second box end, said flanges on said top panel having cut away portions to form opposite triangular and quadrilateral flanges, locking tongues on said side flanges, side sections on opposite sides of said bottom section, and locking tongues on said side sections.

7. A carton blank formed from a single piece 10 of material having defined thereon by score lines 15

an end flange, a top panel, an end panel, a filler section, a bottom panel, and a second end panel, said top panel having side flanges cut away to provide opposite pairs of triangular and quadrilateral side flanges meeting at the apices of the triangular flanges where there is a transverse score line on the top panel, locking means on the flanges and top panel for locking the flanges in cover forming relation to the top panel, side panels on opposite sides of said bottom panel, and locking tongues on opposite ends of said side panels to secure the side panels in box forming position relative to said bottom panel.

BRUCE J. DAVIDSON. 15
